EXHAUST SILENCER FOR INTERNAL COMBUSTION ENGINES

Filed April 24, 1924

Inventor.—
James Neil.
by his Attorneys.—
Howard & Howson.

UNITED STATES PATENT OFFICE.

JAMES NEIL, OF ANNIESLAND, GLASGOW, SCOTLAND.

EXHAUST SILENCER FOR INTERNAL-COMBUSTION ENGINES.

Application filed April 24, 1924, Serial No. 708,771, and in Great Britain October 12, 1923.

My invention has reference to improvements in and relating to exhaust silencers for internal combustion engines, and has for its object the provision of an improved device, 5 wherein the exhaust from an internal combustion engine is passed into a chamber gradually so that it may expand and be discharged from said chamber into the atmosphere easily and freely, in order that the 10 noise attendant upon the shock of a body or volume of gases meeting the atmosphere by sudden or violent expulsion through the engine exhaust pipe may be eliminated or greatly reduced while the back pressure 15 upon the gases due to the inertia of the atmosphere may also be reduced, thereby effecting an economy in the fuel used in said engine.

This invention consists of an exhaust 20 silencer comprising an inner pipe having its one end in open communication with the engine exhaust and its other end in open communication with the atmosphere and a spirally corrugated outer casing forming a 25 spiral chamber around said inner pipe, said chamber being bounded by said pipe and by the spiral corrugation of said outer casing. The inner pipe, which extends through the outer casing and projects from both ends of 30 same, is formed with perforations arranged spirally round the same. The corrugated outer casing may be of conical formation and the spiral corrugation may be of increasing pitch so that the chamber around said 35 inner pipe may have a cross-sectional area which increases from the inlet to the discharge. At a point near the discharge end the inner pipe is plugged. Between said plug and the end of the outer casing adjacent to same the inner pipe is formed with 40 openings so as to pass the gases from the end of the spiral chamber into the end of the inner pipe and out to the atmosphere through the end of the inner pipe. The 45 said plug may be of conical formation.

In order that my said invention and the manner of carrying the same into effect or practice may be properly understood, I have hereunto appended an explanatory drawing 50 which is an elevation, partly in section, of an exhaust silencer as constructed according to this invention.

Referring to said drawing:—

In carrying this invention into effect or 55 practice, the one end *e* of a pipe *a* is connected by means of any suitably constructed

coupling to the engine exhaust pipe. The other end *b* of the pipe *a* is open to the atmosphere. The pipe *a* is provided with a plurality of perforations *c* arranged in the 60 form of a spiral as shown.

Surrounding the pipe *a* is an outer casing *d* which is corrugated with the corrugations arranged spirally so that a spiral chamber *f* surrounds the pipe *a*. By forming the outer casing with corrugations, the external surface of the casing is increased which provides for increased cooling surface.

The corrugated casing *d* may be, as shown, 70 of conical formation, that is, the diameter of the casing *d* at the end *e* of the pipe *a* may be smaller than the diameter at the other end. Preferably, the corrugations of the outer casing are formed as illustrated. Longitudinal sections of the corrugations are of similar configuration. The distance of each corrugation from the pipe *a* and the pitch of the spiral increases as the spiral corrugation is developed around the said 75 pipe so that a chamber of increasing area is provided around the pipe *a*.

At or about the point *g* in the pipe *a* a division wall or plug *o* is arranged or fitted. This plug may be of conical formation as shown so as to diffuse the gases. Between the plug and the adjacent end of the outer casing, openings *n* are formed in the inner pipe *a*.

The exhaust gases pass into the pipe *a* 80 through the end *e* from the engine, then through the perforations *c* into the chamber *f*, back into the pipe *a* through the openings *n* and out to the atmosphere through the end *b*.

I claim:

1. An exhaust silencer for internal combustion engines formed of a perforated inner pipe and an outer casing having a helical corrugation defining a helical chamber around said pipe; one end of said pipe being open to the engine exhaust and the other end of said pipe being open to the atmosphere with a division between said ends substantially as herein set forth.

2. Apparatus comprising a perforated inner pipe; means disposed in said pipe for obstructing the passage of gases therethrough; and a casing surrounding said pipe formed with a helical corrugation so as to form a chamber with increasing cross-sectional area.

3. Apparatus comprising a perforated inner pipe and having a cone disposed within said pipe adjacent to one end thereof; and a helically corrugated outer casing forming a helical chamber around said pipe.
4. An exhaust silencer comprising a pipe having a series of perforations; and a helically corrugated casing surrounding said pipe, said corrugations having an increasing pitch.
5. In combination, an exhaust pipe having a series of perforations; and a helically corrugated casing enclosing said pipe, the radius of said helix corrugation increasing with the length thereof.
6. An exhaust apparatus comprising a perforated pipe; and a helically corrugated casing enclosing said pipe, the pitch and radius of said helix increasing with the length thereof.
7. An exhaust silencer comprising a perforated pipe, having an end obstruction adjacent to one end thereof in the form of a cone with the apex thereof extending toward the inlet end of said pipe; and a helically corrugated casing enveloping said pipe so as to form a helical chamber for the gases passing through said perforations.
8. An exhaust silencer comprising a perforated pipe having an end obstruction adjacent to one end thereof in the form of a cone with the apex thereof extending toward the inlet end of said pipe; and a helically corrugated casing enveloping said pipe so as to form a helical chamber for the gases passing through said perforations, said pipe having an opening intermediate the end of said casing and said obstruction adapted to receive the gases, whereby gases may be discharged from said casing.

JAMES NEIL.
